UNITED STATES PATENT OFFICE

156,869

JEWELRY BOX

Frank D'Alessandro, Buffalo, N. Y.

Application March 25, 1948, Serial No. 145,332

Term of patent 14 years

(Cl. D80—5)

To all whom it may concern:

Be it known that I, Frank D'Alessandro, a citizen of the United States, residing at 75 Sherman Street, Buffalo, New York, have invented a new, original, and ornamental Design for a Jewelry Box, of which the following is a specification, reference being had to the accompanying drawing, forming part thereof.

In the drawing:

Fig. 1 is a front elevational view of a jewelry box, showing my new design;
Fig. 2 is a side elevational view thereof; and
Fig. 3 is a top plan view.

I claim:

The ornamental design for a jewelry box, as shown.

FRANK D'ALESSANDRO.
